(57) **CLAIM**

The ornamental design for a table board, as shown and described.

DESCRIPTION

FIG. 1 is a top perspective view of a table board showing my new design.

FIG. 2 is a front elevation view of the table board shown in FIG. 1.

FIG. 3 is a back elevation view of the table board shown in FIG. 1.

FIG. 4 is a left side view of the table board shown in FIG. 1.

FIG. 5 is a right side view of the table board shown in FIG. 1.

FIG. 6 is a top plan view of the table board shown in FIG. 1.

FIG. 7 is a bottom view of the table board shown in FIG. 1.

FIG. 8 is a cross-sectional view taken along the line 8-8 in FIG. 6.

FIG. 9 is an enlarged view taken from detail 9 in FIG. 8; and, FIG. 10 is a top perspective view showing the top plate of the table board is slidable to an alternative position with respect to the frame of the table board.
